UNITED STATES PATENT OFFICE.

MELVILLE W. HODGE, OF GRAND RAPIDS, MICHIGAN, ASSIGNOR TO EXCELSIOR WRAPPER CO., OF GRAND RAPIDS, MICHIGAN, A CORPORATION OF WISCONSIN.

CHICK-CARTON LINER.

Application filed May 3, 1926. Serial No. 106,447.

The present invention relates to cartons, and more particularly to a liner for cartons intended for the shipment of chicks.

Ordinarily, baby chicks are shipped in cartons having a plurality of compartments, each adapted to receive a dozen or more chicks.

The bottoms of these compartments are covered with material, such as loose excelsior, which is leveled by hand to form a bed for the chicks. These liners are ordinarily produced by taking loose excelsior or wood wool, which is finely cut excelsior, and patting it down to provide a somewhat level bottom liner.

An objection to this practice is that considerable time and labor is required to form a satisfactory bed, and furthermore, it is difficult to mat and compress the excelsior by hand sufficiently to provide a uniformly dense and level bottom liner. The result is that there will frequently result uneven beds and compartments with unfilled corners. Moreover, by hand packing of each compartment with loose excelsior, it is practically impossible to obtain a sufficiently close matting of the fibers to produce a bed which will not disintegrate or become disarranged during shipment. The excelsior layer frequently breaks up, and as a result, chicks come into contact with the bottom of the carton. Furthermore, the smaller chicks become entangled in the loose, fluffy excelsior, and also are frequently smothered, due to the piling up of portions of the layer.

An object of the invention is to provide a bottom liner of substantially carton or compartment dimensions, which is pre-formed, and may be readily placed in one of the compartments, thereby eliminating the time and labor required for arranging the liner from loose excelsior.

A further object of the invention is to provide a liner of excelsior or the like material, which is closely woven or matted, and has sufficient inherent stability to avoid disintegration either before or during use.

A still further object of the invention is to provide a liner which is of substantially uniform thickness and density throughout, thereby preventing smothering of the smaller chicks which frequently occurs in the loose, hand-formed liners, particularly when the same break up and their parts form into piles.

A still further object of the invention is to provide a liner of excelsior or similar material having a readily removable wrapper which assists in maintaining the liner in normal condition until use, the mat or pad of excelsior being preferably withdrawable freely from the wrapper, due to the fact that the latter freely encircles the same.

The above and other objects of the invention will become clearer as the description proceeds in connection with a preferred embodiment shown in the accompanying drawings, wherein:

Figure 1 is a perspective view of a conventional type of chick carton.

Figure 2 is a vertical section of the same with the top in position.

Figure 3 is a perspective view of the improved liner.

Figure 4 is a transverse sectional view.

Figure 5 is a perspective view showing a preferred manner of removing the wrapper.

Figure 6 is a perspective view showing a second method of removing the wrapper from the liner.

The carton illustrated in Figures 1 and 2 forms no part of the present invention, and is simply shown to illustrate the application of an improved liner. The particular type of carton shown comprises a body portion 10 having a series of compartments formed of intersecting partitions 11. The top of the compartment has a perforated inner section 12 spaced by means of wood strips 13 from an outer section 14 to form an air chamber 90 between the two sections. Both the top and body portion may be provided, as illustrated in the several views, with suitable ventilation openings.

Before the present invention, it was customary to cover the bottoms of the compartments with loose excelsior which was pressed down and leveled by hand.

The liner of the present invention is illustrated in Figure 3, and comprises a pad 15 or mat of excelsior which, preferably, is relatively fine, and such as is known in the trade as "wood wool". The excelsior or "wood wool" is compressed and matted or interwoven to provide a pad having sufficient density to prevent the formation of holes therein and the feet of a baby chick from coming in contact with the bottom of a carton. The interweaving or matting of the excelsior is important, for the reason

that the chicks scratch the pad and unless it is relatively dense and of uniform thickness, will quickly form openings through which their feet come in contact with the bottom of the box. The relatively dense pad of the present invention will prevent such contact. Moreover, the interweaving or matting of the excelsior will provide a pad having a sufficient inherent stability to 10 retain its shape, both before and during use, thus eliminating the danger of the chicks being smothered as frequently occurs in the fluffy, loose excelsior inserted by hand.

The compacting of the pad also avoids 15 danger of the chicks becoming entwined or entangled in the liner, which not infrequently occurs when the loose excelsior is used and laid by hand over the bottoms of the compartments.

20 Each pad is cut to substantially the dimensions of the compartments of the cartons, with which it is to be used, and in the present instance, as will be observed, is of oblong shape. It is enclosed by a wrapper 25 16, formed from a strip of paper or suitable material which encircles the liner and has its ends 17 overlapped and adhesively secured together.

Although the form of the wrapper may 30 be varied without departing from the invention, it is desirable that the wrapper encircle the liner freely, and that particular care be taken to see that there is no direct securing of the liner to the pad, as by adhesion, which is likely to occur unless particular care is taken when securing together 35 the ends 17 of the wrapper strip. When a wrapper of this form is used, and it freely encircles the liner, the latter may be readily 40 withdrawn through one open end of the wrapper, as illustrated in Figure 5. Or, if preferred, the wrapper may be torn, as 45 illustrated in Figure 6.

The matting or interweaving of the wood wool and its compression, provides a pad

of sufficient inherent stability to enable it to maintain its form after it is withdrawn from the wrapper, and during use. By holding the liner in the position illustrated in Figure 5, it may be readily deposited in 50 the compartment without handling, thus maintaining the original integrity of the structure, although it will be understood that this deposition of the liner in the compartment when removing the wrapper is 55 not necessary, due to the inherent stability of the structure.

Although the liner is described as being formed of "excelsior" or "wood wool", it should be understood that by these terms, as used in the specification and claims, is meant not merely these particular materials, as such, but also any other material such as grass, straw, or the like which would afford 60 a relatively soft liner.

65 I claim:

1. As a new article of manufacture, a chick carton bottom liner consisting of a body of excelsior matted and compressed to an inherently stable condition, whereby the 70 same does not disintegrate in use, and cut to carton dimensions, and a wrapper in which said body is enclosed, whereby a mercantile unit is provided, said wrapper being freely removable for the purpose described. 75

2. As a new article of manufacture, a chick carton bottom liner consisting of a body of excelsior matted and compressed to an inherently stable condition, whereby the 80 same does not disintegrate in use, and cut to carton dimensions, and an open-ended freely removable wrapper in which said body is enclosed whereby a mercantile unit is provided, the body being freely withdrawable from the wrapper through said open 85 end.

In testimony whereof I have hereunto set my hand.

MELVILLE W. HODGE.
